ELEVATOR CONTROL MECHANISM

Edward Lee Dunn, Livingston, N. J., assignor to
 Otis Elevator Company, New York, N. Y., a
 corporation of New Jersey

Application September 12, 1940, Serial No. 356,439

30 Claims. (Cl. 187—29)

The invention relates to control mechanism for elevators and especially to such mechanism which is actuated in accordance with movement of the elevator car.

There are many control operations for elevator systems which are dependent upon the positions of the cars in their hatchways. In certain installations, for example, push buttons are provided in the car and at the landings for operation by the passengers and intending passengers to register calls and the car is caused to stop automatically at the floors for which calls are registered. In such installations, the calls are picked up in advance of the arrival of the car at the corresponding floors and the slow down and stopping are controlled by mechanism dependent upon the position of the car with respect to the landing at which the stop is being made. Also, mechanism dependent upon the position of the car may be utilized to control the lighting of the hall lanterns at the various floors, dispatching and scheduling of the elevators, door operation and levelling of the car. Although these various control mechanisms may be arranged separately, there is a distinct advantage in grouping them together as a machine driven from the elevator car. Such machines are usually termed selector machines.

In installations in which the slow down and stopping of the car at floors is effected automatically, it is desirable that the speed of the car during retardation be controlled to effect retardation at a rate which is as fast as possible without its being objectionable to the average passenger and such that the car is brought down to a desired low speed from which an accurate stop may readily be made. A variable voltage system, that is, one in which direct current is supplied to the elevator hoisting motor from variable voltage dynamo electric generating means, is particularly suitable for this purpose as the voltage of the generator may be very readily and accurately controlled to control the speed of the elevator car. In higher speed installations, the car cannot get up to full speed in making short floor runs and it has proved a difficult problem to control acceleration and retardation on such runs to bring the car down to a low speed from which an accurate stop may be made, without sacrifice of smoothness of operation, time consumed in making the run, or some other factor of performance.

One of the principal features of the invention is the provision of mechanism for controlling both acceleration and retardation of the car in

such way that these operations are accomplished at the desired rate and so as to bring the car to a desired low speed from which an accurate stop may be made regardless of the length of the run.

5 More specifically, this feature involves distance control of both acceleration and retardation of the car. Thus, by fixing the speed of the car at all points in its travel in accordance with the position of the car with respect to the floor from which it started and with respect to the floor at which a stop is to be made, the same rate of acceleration and retardation may be readily obtained for all lengths of run and accurate stops at the floors may be readily effected.

10 Another feature is the provision of control means effective on short floor runs to cause a decrease in the rate of acceleration to start at a variable distance in advance of the point at which slow down begins, dependent upon the 15 length of the run, to enable acceleration to be obtained for all lengths of run and accurate stops at the floors may be readily effected.

15 Another feature is the provision of control means effective on short floor runs to cause a decrease in the rate of acceleration to start at a variable distance in advance of the point at

which slow down begins, dependent upon the 20 length of the run, to enable acceleration to be reduced to zero by the time the slow down point is reached.

25 There are other features present in the preferred arrangement for carrying out the invention.

According to the preferred arrangement, a plurality of switches are provided for controlling both acceleration and retardation which are operated by means actuated in accordance with movement of the elevator car. In starting the 30 car these switches are closed in a certain sequence as the car reaches points definite distances from the floor from which it started. In slowing down the car, these switches are opened in a reverse sequence as the car reaches points definite distances from the floor at which a stop is being made.

35 According to the embodiment which will be described, this mechanism is arranged so that the distance of car travel on less than full speed runs is divided in half with the first half allotted to accelerating and the last half to retardation. This is a convenient and preferred arrangement, although it is to be understood that other divisions of the length of the run may be adopted.

40 In this arrangement the switches are closed during acceleration through a member which is actuated in accordance with car movement and at a rate which is in effect twice the rate of car movement. This member continues its advance until it has operated all of the switches and thereafter it is moved at the same rate as the car. The member is brought to a stop either during its advance or while in advanced position upon its arrival in effect at a point corresponding to the floor at which a stop is to be made.

Continued movement of the car after this member is brought to a stop effects the reverse operation of said switches to control retardation of the car. In this way the acceleration and retardation portions of the run are made equal and the switches are opened the same distances from the floor at which a stop is being made as the distances from the floor from which the car was started that the switches were closed during acceleration. The operation of the switches is effected through cams which are actuated in one direction to control acceleration and in the reverse direction to control retardation, regardless of the direction of car movement. The control means for arresting acceleration on short floor runs is carried by the member actuated in accordance with car movement.

It is desirable, especially in installations in which hall lanterns are provided for indicating floors at which stops are to be made, to pick up the calls considerably in advance of the arrival of the car at the stopping floor. By arranging the control system so that the proper hall lantern is lighted as soon as the call is picked up, a long advance lighting of the hall lantern is assured. Thus, especially in cases where a plurality of elevator cars are controlled in a group by hall buttons common to that group, intending passengers at the stopping floors are advised as which car is to make the stop in ample time to reach the entrance for that car by the time the car arrives at the floor. In order to provide ample advance lighting of the hall lanterns on short floor runs, the system may be arranged to pick up the call during the closing of the hatchway door and car gate. To effect this operation a movable member, provided with control means for picking out the floors at which stops are to be made, is actuated to an advance position with respect to the car during the closing of the doors and independently of car movement. This control means is arranged to cooperate with stationary control means spaced in accordance with the distance between floors to pick up the calls. After the movable member reaches an advanced position with respect to the car, it is actuated in this advanced position in accordance with movement of the elevator car. This permits a call to be picked up prior to the starting of the car when the car is at a distance from the floor for which the call is registered in which a full speed run cannot be made and on a full speed run upon the arrival of the car a certain distance from the floor. Thus, by lighting the hall lanterns as soon as the calls are picked up, ample advance notification is given to the intending passengers at the floors of the cars which will make the stops.

In addition to the above features, other features and advantages will become apparent from the following description, with reference to a particular application of the invention, and the appended claims.

In the drawings:

Figure 1 is a simplified schematic representation of an elevator installation embodying a selector machine in accordance with the invention;

Figure 2 is a schematic representation of the selector machine;

Figure 3 is a view of the base plate of the selector machine illustrating particularly the driving arrangement;

Figure 4 is a view of the mechanism mounted on the top plate of the selector machine;

Figure 5 is a sectional view taken between the

top and base plates of the selector machine and above the selector machine crossheads;

Figure 6 is an enlarged detail similar to Figure 5 of the selector machine crossheads;

Figure 7 is a side view of the synchronous and distance advance crossheads and the driving arrangement therefor;

Figure 8 is an end view of the same;

Figure 9 is an enlarged detail of switches operated by relative movement of the motor advance and distance advance crossheads;

Figure 10 illustrates the settings of the operating cams for the selector switches;

Figure 11 is a view illustrating the arrangement of the brushes carried by the synchronous and distance advance panels; and

Figure 12 is a similar view illustrating the arrangement of the brushes carried by the motor advance panel.

For a general understanding of a typical elevator installation to which the invention is applicable, reference may be had to Figure 1. An elevator installation has been schematically illustrated in which the car may be controlled as, for example, in the co-pending application of Lewis and Bruns, Serial No. 338,872, filed June 5, 1940. Various parts of the system are indicated by legend. The car is raised and lowered by means of the hoisting motor which drives a traction sheave over which pass hoisting ropes for the car and counterweight. An electromechanical brake is provided and is applied in stopping the car and holding the car when at rest. In the arrangement described in the aforesaid Lewis and Bruns application, current is supplied to the hoisting motor by two generators having their armatures connected in series relation. The two motor generator sets are designated No. 1 MG set and No. 2 MG set. An exciter set is provided, the exciter supplying the current for certain of the field windings and control apparatus. A terminal stopping switch is mounted on the car and is operated by cams at the terminals which engage a roller mounted on the operating arm of the switch to swing it from one operating position to the other.

The invention is illustrated as applied to a system in which the starting of the car is under the control of an attendant in the car, while stops are made in response to buttons pressed by intending passengers at the landings and by buttons pressed in the car by the attendant under the direction of the passengers. The push buttons at the landings, termed hall buttons, are arranged in push button boxes, an up and a down push button being provided at each intermediate floor and one push button at each terminal floor. The push buttons within the car, termed car buttons, are arranged on a car operating panel. On this panel is also arranged the start control switch.

The selector machine is illustrated as driven from the elevator car by a flexible tape secured at one end to the top of the elevator car and at the other end to a reel upon which it is wound and unwound in the driving operation. This reel is mounted on a shaft connected to the selector drive shaft by a chain. Slack in the tape is taken up by a torque motor, which will be referred to as the tape motor. A tape motor brake is applied when the tape motor is deenergized. Should slack develop in the tape, a slack tape switch, through which the tape is attached to the car, is opened to shut down the system. Mechanism is mounted on the end of

the selector drive shaft for operating contacts in accordance with motion of the elevator car and its direction of travel. This mechanism, which is termed a motion device, will not be described in detail.

Reference may now be had to Figure 2, which illustrates schematically a selector machine of preferred construction. This figure is for the purpose of giving a comprehensive understanding of the machine and its operation. It is not intended to show details of construction, such details being illustrated in Figures 3 to 12 inclusive. In the drawings showing details of construction, certain parts not involved in the portion of the mechanism illustrated in any particular figure of drawings are not shown in that figure in order that the construction and operation of the mechanism may be readily understood. For convenience, the selector machine is shown for a five floor installation.

Referring also to Figure 3, the drive tape 30 which winds on and unwinds from reel 31 is secured to this reel by a pin 32. The reel is secured to a shaft 33 supported in bearing plates 34 mounted on a base 35. This shaft is connected through gears 36 and 37 to the shaft 38 of tape motor TM. Also arranged on this shaft is the brake pulley 41 to which the tape motor brake shoes 42 and 43, shown in section, are applied. The tape motor is energized while the car is in service to exert a torque in a direction tending to wind up the tape on the reel, that is, to turn the reel counterclockwise as viewed from the right in Figure 3. Thus, during upward movement of the car the tape motor winds up the tape on the reel, while during downward movement the tape is unwound from the reel by the car against the torque of the tape motor.

Also secured to shaft 33 is a sprocket wheel 45. This sprocket wheel is connected by sprocket chain 46 to another sprocket wheel 47 secured to selector drive shaft 48. Thus shaft 48 is driven counterclockwise, as viewed in Figure 3, during upward movement of the car. A tensioning sprocket wheel 50 is mounted on an arm 51 rotatively mounted on drive shaft 48. The drive shaft is supported by bearing stands 52 mounted on the selector base plate 53. The base plate is connected to the top plate 54 by angle members 55 secured to these plates at the corners (see also Figure 4), thereby forming a frame.

The selector machine has three moving crossheads, indicated in Figure 2. One of these crossheads, designated 56, is driven by means of a motor AM mounted on the top of top plate 54. This crosshead will be termed the motor advance crosshead and the motor the advancer motor. The other two of these crossheads are actuated in accordance with car movement. One of them, designated 58, will be termed the synchronous crosshead and the other, designated 60, being driven in the ratio of 2:1 with respect to the synchronous crosshead, will be termed the distance advance crosshead.

Referring also to Figures 4, 5, 6 and 8, the advancer motor AM operates through reduction gears 61, 62, 63 and 64 to drive a sprocket wheel 65. The sprocket wheel and gear 64 are secured to a shaft 66 supported by bearing plates 67 secured to the base 68 for the motor. Gears 62 and 63 are mounted on another shaft 70, also supported by bearing plates 67, while gear 61 is secured to the end of the motor shaft. The sprocket wheel drives a sprocket chain 71 secured at one end to the top of the motor advance cross-

head 56, from which it extends upwardly and around the sprocket wheel, downwardly through a cylindrical tube 72 extending between the top and bottom plates, thence around an idler sprocket 73 secured to the bottom of the base plate 53 and thence upwardly to the bottom of the motor advance crosshead, to which the other end of the chain is secured. The ends of the chain are secured to the crosshead by adjusting bolts 74 to enable any slack in the chain to be taken up. A counterweight (not shown) for the motor advance crosshead is arranged within tube 72 and connected to the sprocket chain.

The motor advance crosshead is guided in its movement by a rod 75 extending between the top 233 and bottom 234 of the synchronous crosshead 58. This rod extends through apertures in guide members 76 formed on the crosshead. The opposite end of the crosshead is formed with 20 prongs 77 to span a bar 78 extending between the top and bottom of the synchronous crosshead, thereby forming a supplementary guide for the motor advance crosshead. Stops 80 and 81, adjustably mounted on rod 75, limit the movement 25 of the motor advance crosshead with respect to the synchronous crosshead.

The motor advance crosshead carries a frame 82 upon which are mounted a plurality of circuit controlling elements for cooperating with stationary circuit controlling elements mounted on floor bars 83, one for each floor served by the car. These floor bars are spaced in accordance with the distance between the floors for which they are provided and are mounted on rods 84 secured to the bottom and top plates of the selector machine. Each floor bar comprises an elongated flat bar 85 spanning rods 84 and secured thereto by means of angle clamps 86 and screws 87, as shown in Figure 5. The bar is provided with a plurality of spaced apertures utilized in the present arrangement for mounting a plurality of spring contacts. These spring contacts are mounted on the floor bars through insulating bases 88 in the same manner as disclosed in the co-pending application of Edward Lee Dunn, Serial No. 214,271, filed June 17, 1938, in connection with Figure 13 thereof. Also, the construction of the spring contacts is the same as that of spring contact 193 of that application. It is believed, therefore, that these spring contacts need not be further described here.

In the control system of the aforementioned Lewis and Bruns application, one of these spring contacts, designated CP, serves for an intermediate floor as a call pick up contact for calls registered by the pressing of the car button for that floor. There is one of these contacts on each floor bar. The next spring contact to the right, as viewed in Figure 5, which is designated PH, serves as a call pick up holding contact. There is one of these contacts on each floor bar. The next spring contact to the right, designated DHP, serves as a down hall call pick up contact. There is one of these contacts on each of the floor bars except the floor bar for the upper terminal floor. The next spring contact to the right, designated UHP, serves as an up hall call pick up contact. There is one of these contacts on each of the floor bars except the floor bar for the lower terminal floor. The last spring contact, designated AP, serves as an auxiliary pre-retardation control contact. There is one of these contacts on each floor bar.

The crosshead frame 82, which carries the various elements for contacting with the spring

contacts above described, is secured to the cross-head by means of strap 90 and angle 91. The frame is provided with a mounting panel for the contacting elements. Referring also to Figure 12, this panel, which is of insulating material, is arranged in duplicate sections 92 secured to the frame in abutting relationship. This panel will hereinafter be referred to as the motor advance panel. The various contacts cooperating with the spring contacts on the floor bars are secured to brackets adjustably mounted in slots in the panels. This arrangement is the same as that described in the aforementioned co-pending Dunn application, and will not be further described. The contact for engaging spring contacts CP is designated CPB and serves as the car call pick up brush. The contact for cooperating with spring contacts PH is designated PHB and serves as the call pick up holding brush. This brush is a relatively long one as compared with brush CPB. The brushes for cooperating with spring contacts DHP and UHP are designated DHB and UHB respectively, these contacts serving as the down hall call pick up brush and the up hall call pick up brush respectively. These brushes also are relatively long and each is divided into a leading section 93 and a trailing section 94. The contact for cooperating with spring contacts AP is designated APB and serves as the auxiliary pre-retardation control brush. This brush also is a relatively long brush.

The motor advance crosshead also carries a pair of switches (see Figure 9), one effective for upward movement of the crosshead and the other for downward movement. The up motor advance switch, designated MAU, extends upwardly from the crosshead, while the down motor advance switch, designated MAD, extends downwardly from the crosshead. These switches are mounted on a mounting plate 95 secured to the crosshead. Each of these switches is of the same construction which is described in the aforementioned co-pending Dunn application wherein the switches are shown in Figures 10 and 14.

Each switch comprises a frame 96 of molded insulating material secured to the mounting plate. A pair of leaf springs 97 is secured by terminal screws to the frame. Protecting stops 98 are formed on each side of the frame, between which the contact springs extend. The movable contact comprises a lever 100 pivotally mounted on a pin supported on the frame and having its upper end 101 bent toward the contact springs. A bridging member in the form of an angle 102 is secured to the bent end of the lever. The lever is biased by a spring 104 to a position where member 102 bridges the contact tips of the contact springs. The lever is channel shaped and lugs are formed on the sides of the channel to form a support for the pivot pin of operating roller 105. This roller is positioned in the path of movement of cam 106 secured to distance advance panel 60, the arrangement being such that with the car stopped at the floor the rollers of both switches are engaged, causing these switches to be open.

Reference may now be had to Figures 2, 5, 6, 7 and 8. The distance advance crosshead 60 is guided in its movement on the cylindrical tube 72 and on another cylindrical tube 110, also extending between the top and base plates of the selector. An aperture 111 is provided in the crosshead through which tube 72 extends. Guide shoes 112 engage tube 110, these guide shoes being held in place by screws 107 extending

through arms 108 and 109 formed by bifurcating the crosshead, the screws being held in position by lock nuts.

The distance advance crosshead carries a pair of oppositely disposed pawls 113 and 114 for cooperating with stopping lugs 115 mounted on an elongated rod 116. Each pawl is pivotally mounted on a pivot pin 117 extending from a bracket 119 secured to the crosshead. Each pawl is provided with a spring 118 for biasing it into position for cooperation with the stopping lugs. Lug 120 formed on each pawl cooperates with bracket 119 to limit the outward movement of the pawl.

The stopping lugs 115 are carried by collars 121 adjustably mounted on rod 116. A stopping lug is provided for each floor, the collars being in spaced relation on rod 116 in accordance with the distance between the floors for which they are provided. The collars are split to permit adjustment and clamping thereof to the rod, the collars being clamped in adjusted positions by bolts 122. Each stopping lug is provided with a threaded stem 123 which extends through an aperture 124 in supporting arm 125 formed on the collar. A shoulder 126 is formed on this arm, against which the lug fits to prevent rotative movement thereof. The lug is clamped in its proper position by means of a nut 127 on the threaded end of the stem.

The stopping lugs are retracted during movement of the crosshead into position where the pawls clear the lugs. The lugs are maintained retracted until the car arrives at a certain distance from the landing at which a stop is to be made. When this condition is reached, the lugs are released and move into position for cooperation with the pawls. This operation is controlled by an electromagnet, termed the pawl magnet and designated SM, mounted on the bottom of top plate 54. This magnet, as shown in Figures 2 and 4, operates a lever 128 pivotally connected to the movable core 130 which extends into the magnet through an aperture 131 in the magnet frame 132. The lever is biased to unattracted position by a spring 133 arranged between the lever and the magnet frame. A screw 129 adjustably mounted on the other end of the lever engages an abutment 139 extending between the top and bottom plates of the magnet frame to limit the movement of the lever by spring 133. The lever is formed on a sleeve 134 secured as by a pin to a pivot shaft 135 rotatably mounted in the top and bottom plates 136 of the magnet frame. The pivot shaft extends below the magnet frame, where it is secured by bolt 137 to the rod 116, the rod in turn being pivoted in the base plate 53 of the selector.

A bar 138 secured to lever 128 controls the operation of pawl magnet switch SM!. This switch, which is of the same construction as the switch shown in Figure 9, is pivotally mounted on selector top plate 54 and is biased by spring 140 to closed position. Operating roller 141 of the switch is engaged by bar 138 when the pawl magnet is deenergized to maintain the switch in open position against the force of spring 140.

Upon energization of the pawl magnet its movable core is pulled inwardly or clockwise as viewed in Figure 2, causing clockwise rotative movement of lever 128. This moves bar 138 away from roller 141, permitting spring 140 to close switch SM!. It also rotates rod 116 clockwise, which retracts the stopping lugs into position where they are clear of the pawls. When

this has been done, the distance advance cross-head is free to move.

The distance advance crosshead is driven from the selector drive shaft 48 through the intermediary of a sprocket chain 142. This chain is driven by a sprocket wheel 143 which is secured to a shaft 144. As shown in Figure 3, this shaft is supported by bearings stands 145 mounted on selector base plate 53. The shaft is driven by a bevelled gear 146 secured to the shaft, this gear in turn being driven by a small bevelled gear 147 secured to selector drive shaft 48. Thus sprocket wheel 143 is driven clockwise, as viewed in Figure 2, during upward car movement and counterclockwise during downward car movement.

Sprocket chain 142 is an endless chain extending upwardly from sprocket wheel 143 around an idler sprocket wheel 148 above the top plate of the selector. This wheel is rotatably mounted on lever 150, in turn pivoted to bracket 151 secured to top plate 54. The opposite end of the lever is held between two nuts arranged on an adjusting screw 152 secured to top plate 54, this arrangement being provided to take up any slack in the chain.

Chain 142 engages a sprocket wheel 155 pivotally mounted on a stub shaft 156 secured to a plate 157 which, in turn, is secured to distance advance crosshead 60, as shown in Figures 6, 7 and 8. A bushing 158 is provided in an aperture in the sprocket wheel to form a bearing. The chain is maintained in meshing relationship with the sprocket by a shoe 160 secured to plate 157. A clutch device 161 is provided to hold sprocket 155 against rotative movement with respect to stub shaft 156. This clutch comprises two discs 162 and 163 with a ring 164 of brake lining material arranged between them. The inner disc 162 is secured as by screws to the sprocket wheel 155. It is provided with an annular shoulder 165 to locate the ring 164. The outer disc 163 is formed with a pair of lugs 166 which straddle a pin 167 secured to plate 157. This prevents the rotative movement of disc 163 with respect to stub shaft 156, while allowing linear movement of the disc on the shaft. The discs and ring are pressed together by the spring 168 arranged on the stub shaft between a spring seat 170 and a boss 171 formed on disc 163. A cotter pin 172 holds spring seat 170 in position to maintain spring 168 in a state of compression. With this arrangement, upon movement of sprocket chain 142, rotation of sprocket wheel 155 is prevented by the clutch device so that the distance advance crosshead 60 is carried along with sprocket chain 142 in accordance with movement of the elevator car.

As shown in Figure 2, a chain 175 is adjustably secured at one end to the top of distance advance crosshead 60, from which it extends upwardly to and around an idler pulley 176 pivotally mounted on a bracket 177 secured to top plate 54. From this pulley, the chain extends downwardly through cylindrical tube 110 to and around another idler pulley 178 pivotally mounted on a bracket 180 secured to the bottom of base plate 53 and thence upwardly to the bottom of crosshead 60 to which the other end is adjustably secured. A counterweight (not shown) for the distance advance crosshead is provided within tube 110 and connected to this sprocket chain.

The distance advance crosshead carries a frame 182 similar to frame 82 and carrying a

plurality of circuit controlling elements for co-operating with stationary circuit controlling elements on floor bars 183, one for each floor served by the car. These floor bars are spaced in accordance with the distance between the floors for which they are provided and are mounted on rods 184 secured to the bottom and top plates of the selector machine. These floor bars are of the same construction and are secured in the same way to the rods as floor bars 83. Also, spring contacts are mounted on these floor bars the same as on floor bars 83. Four spring contacts are arranged on each floor bar (see Figure 5). Two of these contacts are of the same construction as spring contact 193 of the aforementioned co-pending Dunn application. The other two contacts are arranged for mutual cooperation and are of the same construction as spring contacts 186 and 187 of the aforementioned co-pending Dunn application. In the control system of the aforementioned Lewis and Bruns application, the spring contact designated 1PR serves as the first pre-retardation control contact for the floor for which it is provided. The spring contact designated 2PR serves as the second pre-retardation control contact for the floor for which it is provided. The remaining mutually cooperating spring contacts, which are designated AS, serve as auxiliary starting relay control contacts for the particular floor for which they are provided.

The crosshead frame 182 which carries the elements contacting with the spring contacts just referred to is secured to the distance advance crosshead by means of straps 190 and is provided with a panel hereinafter termed the distance advance panel. Referring to Figure 11, this panel, as in the case of the motor advance panel, is arranged in duplicate sections 192 in abutting relationship. The contacts are mounted on these sections the same as the contacts on section 92. Two spaced contacts are provided for engaging spring contacts 1PR, one effective for up car travel and one effective for down car travel. The up contact is designated 1UPB and serves as the first up pre-retardation brush. The down contact is designated 1DPB and serves as the first down pre-retardation brush. Two spaced contacts are provided for engaging spring contacts 2PR, one effective for up car travel and one effective for down car travel. The up contact is designated 2UPB and serves as the second up pre-retardation brush. The down contact is designated 2DPB and serves as the second down pre-retardation brush. One of the spring contacts AS for each floor is provided with an outer contact tip which is engaged by an elongated contact designated ASB mounted on one of panel sections 192. This contact serves as the auxiliary starting relay control brush.

Sprocket wheel 155 meshes with another sprocket chain 193 arranged on the side of the sprocket wheel opposite from chain 142. Chain 193 is maintained in meshing relationship with the sprocket by shoe 194 secured to plate 157. The chain is an endless one, extending around sprocket wheels 195 and 196 at the top and bottom respectively of the selector machine. Sprocket wheel 196 is rotatably mounted on lever 197, in turn pivoted to bracket 198 secured to base plate 53. The opposite end of the lever is held between two nuts arranged on an adjusting screw 200 secured to base plate 53, this arrangement being provided to take up any slack in the chain.

Referring to Figure 4, sprocket wheel 195 at

the top of the selector is mounted on a shaft 202 rotatably supported in bearing stands 203 and 204 provided on base 205 secured to top plate 54. Ratio gears 206 and 207 are provided for transmitting the rotation of shaft 202 to another shaft 208 also supported in bearing stands 203 and 204, gear 206 being secured to shaft 202 and gear 207 being secured to shaft 208. Arranged on the other end of shaft 208 beyond bearing stand 204 is a uniform motion cam 210, the contour of which is shown in Figure 2. This cam is arranged to effect linear movement of a frame 211 through the intermediary of rollers 214 and 215 pivotally mounted on the frame. This frame slides on a rod 212 secured to bearing stand 204. The frame comprises two side plates connected by yokes 213. These yokes are provided with apertures through which rod 212 extends. A screw 219, extending through a slot in one of the side plates and secured to stand 204, prevents the frame from turning on the rod. The rollers are mounted on stub shafts 216 and 217 secured to frame 211. Stub shaft 216 has an extension 218, which is to be engaged by stop member 220 secured to cam 210 to bring the cam to a stop, upon its rotation in either direction from the neutral position illustrated in Figure 2 through an angle slightly less than 180°.

With this arrangement, movement of distance advance crosshead 60 by chain 142 causes movement of chain 193 along with the crosshead. This causes rotation of cam 210 through sprocket wheel 195 and ratio gears 206 and 207 in a direction from neutral depending upon the direction of movement of the distance advance crosshead. Upon the engagement of stop member 220 with extension 218, cam 211 is brought to a stop, which brings chain 193 to a stop. Continued movement of chain 142 causes sprocket wheel 155 to roll on chain 193 as a rack, clutch 161 yielding to permit rotation of sprocket wheel 155 on shaft 156. Thus, after movement of chain 193 is stopped by the engagement of stop member 220 with extension 218, continued movement of the distance advance crosshead takes place at half the speed of chain 142 instead of the same speed as it did prior to the stopping of chain 193.

Uniform motion cam 210 is utilized to effect the operation of a plurality of switches arranged on the top of the selector machine. A rack 221 is secured to frame 211 so as to move linearly therewith. This rack engages a pinion 222 arranged on a cross shaft 223 supported by bearing stands 224 and 225 secured to top plate 54. The switches are operated by cams arranged on the cross shaft to be operated by the rack and pinion. These switches are mounted in spaced relationship on a cross bar 226 extending between and supported by bearing stands 224 and 225. The switches are of the same construction as that illustrated in Figure 9, seven of them being provided with making contacts and four of them with breaking contacts. These switches are principally for controlling acceleration and retardation of the elevator car and will hereinafter be referred to as selector switches.

By effecting rotative movement of shaft 223 upon which the operating cams for the selector switches are mounted, by a uniform motion cam, the motion of shaft 223 is effected in direct proportion to the movement of the distance advance crosshead and therefore to the movement of the elevator car. Also, shaft 223 is rotated in the same direction by this cam during its movement from neutral position, regardless of the direction

of rotation of the cam and therefore regardless of the direction of travel of the car. The size of pinion 222 is chosen so that shaft 223 rotates at twice the speed of shaft 238. Thus nearly a full revolution of shaft 223 is effected before the uniform motion cam is brought to a stop. This is an advantage in setting the operation of the selector switches. Also, with this arrangement cams of uniform construction can be employed for operating all the switches. A pair of cams 228 are provided for each switch, these cams being arranged on shaft 223 in position to engage the operating rollers of the switches for which the cams are provided. Each cam is a 180° cam, provided with a split hub, a screw extending across the split portion of the hub being provided to clamp the cam to the shaft. Inasmuch as shaft 223 is rotated in the same direction for each direction of car travel, a correct setting of each cam for one direction of car movement is correct for the opposite direction of movement.

In the control system of the aforementioned Lewis and Bruns application, only a certain number of the selector switches which may be provided on the top of the selector are utilized. A sequence diagram for the switches utilized is indicated in Figure 10. Each of these switches is designated by the letters SS with a numeral appended thereto to differentiate between them. These switches, being operated in accordance with the movement of the elevator car, are operated when the car reaches points certain distances from the floor as the car leaves that floor in starting. These distances are determined by the setting of the cams, in turn determined by the particular control operations performed. As will be shown later, reverse operation of these switches takes place during stopping of the car at a floor as the car reaches points the same distances from this floor as the distances of the points at which these switches operated during starting from the floor from which the car started.

Selector switches SS3, SS4 and SS5 control the acceleration of the car while these switches and switches SS1 and SS2 control retardation. Switch SS1 controls the operation of the brake under certain conditions. Switches SS8 and SS9 control the effectiveness of the first and second pre-retardation brushes. Switch SS11 controls the automatic opening of the hatchway door and car gate in stopping. Switch SS12 controls initiation of slow down from a full speed run. Switch SS13 controls the circuits for certain of the accelerating switches. The actual setting of the switches is determined by the particular installation. In the control system illustrated in the aforementioned Lewis and Bruns application, it has been found that for certain apparatus and a full speed of 800 feet per minute the cams may be set to operate their switches substantially as follows: switch SS1 upon 6° of rotative movement of the operating cams out of neutral; switch SS2 upon 27° of rotative movement; switch SS3 upon 43° of rotative movement; switch SS4 upon 95° of rotative movement; switch SS5 upon 186° of rotative movement; switch SS7 upon 1° of rotative movement; switch SS8 upon 28° of rotative movement; switch SS9 upon 75° of rotative movement; switch SS11 upon 18° of rotative movement; switch SS12 upon 308° of rotative movement; and switch SS13 upon 10° of rotative movement.

The uniform motion cam is brought to a stop after approximately 315° of rotative movement

of the cams. For 800 feet per minute full operating speed of the car, this 315° movement of the cams is effected in 25 feet of car travel, the ratio of gears 206 and 207 being chosen so that for a given size sprocket wheel 195 this relationship is obtained.

The distance advance crosshead carries cam members 230 and 231 for operating switches carried by the synchronous crosshead 58. These cam members are secured to the top and bottom of frame 182. The switches operated by these cam members are of the same construction as those illustrated in Figure 9 and therefore will not be described. One of these switches is effective for upward movement of the distance advance crosshead and the other for downward movement. These switches will be hereinafter referred to as up distance advance switch DAU and down distance advance switch DAD. These switches are mounted on the panel mounting frame 232 carried by the synchronous crosshead.

The synchronous crosshead comprises an upper cross member 233 and a lower cross member 234 joined by side members 235 and 236. This crosshead is guided by the cylindrical members 72 and 110, an aperture 237 being provided in the top member of the crosshead and another aperture 238 being provided in the bottom member of the crosshead to receive cylindrical member 72. Both the top member and the bottom member of the crosshead are provided with guide shoes 240 for engaging tube 110, these guide shoes for each member being held in place by screws 241 extending through arms 242 and 243 formed by bifurcating this portion of the crosshead, the screws being held in position by lock nuts 244. Side member 236 is in the form of a channel and is secured to the arms 242 and 243 of the top and bottom members. The guide rod 75 for the motor advance crosshead is secured in lugs 245 formed on the top and bottom members of the synchronous crosshead. The guide bar 78 for the motor advance crosshead is secured in lugs 246 formed on the top and bottom members of the synchronous crosshead.

Side member 235 of the synchronous crosshead is in the form of a plate extending from the top and bottom members of the synchronous crosshead. The frame 232 is secured to this plate by means of a strap 247. Spring contacts of the same construction as spring contacts CP are mounted on floor bars 183. In the control system of the aforementioned Lewis and Bruns application, one of these contacts serves to control certain levelling operations upon an overrun and is designated OV. There is one of these contacts for each floor. The other spring contact controls direction and is designated CD, these contacts being provided only on the floor bars for the terminal floors. These spring contacts are adapted to be engaged by contacts mounted on duplicate panel sections 249 secured to frame 232. The contact for engaging spring contacts OV is designated OVB, while the contact for engaging spring contacts CD is designated CDB.

The synchronous crosshead is driven by chain 142. A sprocket wheel 250 is secured to a jack shaft 251 rotatably supported in the bottom member 234 of the crosshead. This sprocket wheel meshes with the left hand run of the chain, a shoe 252 being secured to the bottom member of the crosshead in position to maintain the chain in meshing relationship with the sprocket wheel. Secured to the other end of

shaft 251 is a similar sprocket wheel 253. On the right hand side as viewed in Figure 2, this sprocket wheel meshes with a stationary chain 254, a shoe 256 being secured to the bottom member of the crosshead in position to maintain the chain in meshing relationship with the sprocket wheel. This chain is secured to and extends between base plate 53 and top plate 54 of the selector, adjusting screws 255 being provided to secure the chain to the plates. With this arrangement, upon movement of drive chain 142, sprocket wheel 253 is driven through sprocket wheel 250 and shaft 251, causing it to roll on stationary chain 254 as a rack. This movement occurs in the same direction as the movement of the left hand run of chain 142 as viewed in Figure 2, but at one-half the speed. The floor bars, as previously pointed out, are spaced in accordance with the distances between the floors for which they are provided. The setting of the floor bars is in accordance with the ratio of the movement of the synchronous panel with respect to the movement of the elevator car. Thus, from the standpoint of the setting of the floor bars, the distance advance crosshead initially moves at twice the speed of the elevator car until stop member 220 on the uniform motion cam 210 engages extension 218 of the stub shaft 216. From then on, due to the slipping of clutch device 161, the distance advance panel moves at the same speed as the elevator car, in unison with the synchronous panel.

When the car is stopped at a floor all the crossheads and therefore all the panels are in neutral position with respect to the floor bar for the floor at which the car is stopped. In the control system illustrated in the aforementioned Lewis and Bruns application, in starting the car, the advancer motor is energized, prior to the starting of the car, to move the motor advance panel upwardly if the car is being started in the up direction, and downwardly if the car is being started in the down direction. Movement of the motor advance panel takes place rapidly. During the initial movement of the motor advance panel, the motor advance switch for the corresponding direction of travel is closed by the disengagement of its operating roller from cam 106. If the car is being started in the up direction switch MAU is closed and if the car is being started in the down direction switch MAD is closed. The closing of either switch causes the energization of pawl magnet SM to retract the stopping lugs, which frees the distance advance panel for movement. Upon the motor advance crosshead engaging its stopping collar, the advance of the motor advance panel is discontinued. This preferably takes place before the car is actually started.

As the car starts, the synchronous panel and the distance advance panel are both moved in the direction in which the car is started, the synchronous panel moving in accordance with the speed of the elevator car with respect to the floor bars and the distance advance panel moving at twice car speed with respect to the floor bars. Movement of the synchronous panel permits movement of the motor advance panel to keep the motor advance crosshead against its stop. As relative movement of the distance advance and synchronous panels takes place, distance advance switch DAU or DAD for the direction in which the car is moving is closed by the disengagement of its operating roller from cam member 230 or 231 respectively. Movement of the

distance advance crosshead causes operation of the selector switches in sequence, thereby controlling the acceleration of the car in accordance with the distance the car moves. Assuming that a run is to be made which will permit the car to attain full speed, the distance advance panel continues its advance with respect to the synchronous panel until fully advanced, whereupon relative movement between the distance advance panel and the synchronous panel is stopped by the engagement of stop member 220 with extension 213. From this point on until a call is picked up, the three panels move as a unit at the same speed.

When a call is picked up the advancer motor is deenergized. A call is picked up by the engagement of brush CPB with an "alive" one of contacts CP or by the engagement of up brush UHB during up car travel or down brush DHB during down car travel with an "alive" one of its cooperating stationary contacts. When the advancer motor becomes deenergized, the motor advance panel comes to a stop. This takes place very quickly, so that the motor advance panel comes to rest in neutral position with respect to the floor bar for the floor for which the call is picked up and the brushes on the panel are maintained in engagement with the contacts for the floor for which the call is picked up. The distance advance panel and synchronous panel continue to move in accordance with car movement, catching up with the motor advance panel.

Just before the distance advance panel catches up with the motor advance panel, the operated motor advance switch MAU or MAD is opened, which causes the deenergization of pawl magnet SM. This releases the stopping lugs 115 to extend them into the path of movement of the pawls. The stopping lug for the floor for which the call has been picked up is thereupon engaged by the pawl for the direction in which the car is travelling, pawl 113 serving as the up pawl and pawl 114 serving as the down pawl. This brings the distance advance crosshead to a stop. This is in neutral position with respect to the floor bar for the floor at which the stop is to be made, at which time the auxiliary starting relay control contacts AS for that floor are opened by their brush ASB.

Inasmuch as the car continues in motion after the distance advance crosshead is brought to a stop, chain 142 continues to drive the synchronous crosshead in accordance with movement of the elevator car. Owing to the fact that the distance advance crosshead is stopped, chain 142 also acts to rotate sprocket wheel 155 counterclockwise as viewed in Figure 2 in case of up car travel and clockwise in case of down car travel, clutch device 161 yielding to permit this rotative movement. In doing so, sprocket wheel 155 drives the right hand run of chain downwardly in case of up car travel and upwardly in case of down car travel. Considered from the standpoint of distance between floor bars, this occurs at twice the speed of the elevator car. Thus as the car continues its movement, the operated cams for the selector switches are gradually returned to neutral position, causing restoration of the selector switches to their former positions at distances from the floor at which the stop is being made corresponding to the distances from the floor from which the car was started that these switches were respectively operated. This causes the car to be slowed down, providing distance control of the retardation of the car. The

final stopping of the car at the floor is controlled by the levelling mechanism, which will be described later. Just before the car reaches the floor, selector switch SS11 opens to cause the opening of the car gate and hatchway door. During this slow down operation, the synchronous crosshead, continuing its movement, gradually catches up with the distance advance and motor advance crossheads. Just before the car comes to a stop the operated distance switch DAU or DAD is opened. When the car is brought to a stop at the floor the synchronous crosshead also stops, this occurring with the synchronous panel in neutral position with respect to the floor bar for the floor at which the stop is being made.

It may happen that a call is picked up by a brush on the motor advance panel before this panel reaches fully advanced position. Under such circumstances the advancer motor is immediately deenergized, bringing the motor advance panel to a stop with its brushes in engagement with the stationary contacts for the floor for which the call is picked up. Upon the car being started, the synchronous panel and distance advance panel are moved by the car in the same manner as on the full speed run above described. However, when making a short floor run, the pre-retardation brushes PB, in cooperation with their respective stationary contacts for the floor for which the call is picked up, the effective pre-retardation brush being dependent upon the direction of car travel and the length of the run, act in advance of the point at which slow down begins to decrease the rate of acceleration. Just before the distance advance panel catches up with the motor advance panel, operated switch MAU or MAD opens, causing deenergization of the pawl magnet SM. The stopping lugs are released and the lug for the floor for which the call is picked up is engaged by the pawl for the direction in which the car is travelling. This causes reverse operation of the operated selector switches to slow down the car and finally bring it to a stop at the floor for which the call has been picked up. Thus on a short floor run as well as a full speed run distance control of acceleration and retardation is provided.

Reference may now be had to Figures 2, 4 and 5, which illustrate the mechanism for bringing the car to an exact landing level. This levelling mechanism is illustrated as arranged on the selector machine. The synchronous crosshead 58 carries a frame 250. The top and bottom members 261 and 262 of the frame are provided with vertically aligned apertures 263 to receive tubular members 264 and 265. These tubular members are rotatably mounted in the apertures, bushings (not shown) being provided in the apertures to form bearings for the tubular members. Sleeves 266 and 267 are secured as by screws 258 to tubular members 264 and 265 respectively. These sleeves are positioned between the top and bottom members of frame 250, thereby holding the tubular members in definite positions vertically with respect to the frame. The tubular members are arranged to slide vertically on square rods 268 and 269 extending between the top and base plates of the selector machine. These rods are rotatably supported in bearings 270 provided in the base plate 53 and are likewise rotatably supported at the top through extension members which will be described later. Although the tubular members slide upon the rods as movement of the synchronous crosshead takes place, they cannot turn with respect to the rods, so

that any pivotal movement of these members is imparted to the rods and any pivotal movement of the rods is in turn imparted to the tubular members.

Secured to bottom member 262 of the frame 260 is a bracket 270. This bracket extends downwardly from the frame and has mounted thereon eight switches arranged in columns of four each. These switches are of the same type as those illustrated in Figure 9, three of them in each column being spring biased to contact engaging position and the other in each column being biased into position with the contacts separated. The switches in the left hand column as viewed in Figure 2, designated L1U, L2U, L4U and L3U, serve as up levelling switches, while those in the right hand column, designated L1D, L2D, L4D and L3D, serve as down levelling switches. Each of the up levelling switches is provided with an operating cam 271 adjustably clamped to the tubular member 264. Each of the down levelling switches is provided with an operating cam 272 adjustably clamped to the tubular member 265. Each of these cams is of the same construction and comprises a lever 273 having a cam formation 274 on its outer end for engaging the operating roller 275 of the switch for which it is provided. The inner end of the lever and a yoke member 276 form a split hub which is clamped to the tubular member by screws 277.

Rotative movement of the tubular members to operate the levelling switches during the levelling operation is effected by operating arms 278 and 280 formed on sleeve members 266 and 267 respectively. Each arm is provided with a roller 281 at its outer end, this roller being supported by roller carrier 282 secured to the end of the arm by a screw 283. These operating arms are operated by a plurality of cams 284, one for each floor. These cams are arranged in spaced relation on a vertical shaft 285. This shaft is rotatably supported at its lower end by thrust bearing 286 arranged in bearing stand 287 secured to base plate 53. At the top this shaft is similarly supported in a bearing 288, the housing for which is secured to the top plate 54. This shaft is driven by shaft 48 through bevelled gears 290 and 291, gear 290 being pinned to shaft 48 and gear 291 being pinned to shaft 285.

The cams are spaced along the cam shaft so that the distances between adjacent cams are in accordance with the distances between the respective floor landings considered from the standpoint of travel of the synchronous cross-head 53. These cams are all similar in construction and each comprises a cam portion 292 and a yoke portion 293. Screws 289 extend through apertures in the yoke portion and are threaded into the cam portion to bind the cam to the cam shaft. The cam portion forms substantially a 180° cam. The radius of the working face 294 of each cam is a maximum at the central portion thereof and a minimum at the end portions. The end portions are bevelled at 295. Each of the cams is helical and has a pitch equal to the travel of the synchronous crosshead per revolution of the cam shaft. Each cam is set radially so that when the car is at rest at the floor for which the cam is provided, the operating rollers 281 on the ends of operating arms 278 and 280 are at points immediately adjacent the end portions 295 of the cam. As will be seen from later description, these rollers are disengaged from the effective surface of the cam at this time. 75

The operating cams 271 and 272 for the levelling switches are set on the tubular members 264 and 265 respectively so as to cause, under these conditions, the contacts of levelling switch L1U, L2U, L4U, L1D, L2D and L4D to be separated and the contacts of levelling switches L3U and L3D to be engaged.

When the car is to be started, the square rod 268 is rotated counterclockwise and square rod 269 is rotated clockwise as viewed in Figure 2 to move the operating arms 278 and 280 into positions where the operating rollers carried thereby are clear of the levelling cams during operation of the car. The amount of this movement is sufficient to move the operating cams 271 and 272 for the up and down levelling switches respectively into positions to permit the closing of levelling switches L1U, L2U, L4U, L1D, L2D and L4D by their springs and the opening of levelling switches L3U and L3D by their springs. This movement of rods 268 and 269 is effected by the levelling magnet LEV.

The levelling magnet comprises a coil 296 mounted in a frame 297 secured beneath top plate 54 of the selector machine. This coil is arranged on a non-magnetic sleeve (not shown) held between the side plates 298 of the frame. The magnet is provided with movable cores 300 and 301. These cores are provided with telescopic ends and extend into the magnet coil. The outer ends of the cores are pivotally connected by links 302 to the arms 303 of the levers 304 and 305 for cores 300 and 301 respectively. These levers are secured to shafts 306 pivotally mounted in bearings provided in top plate 279 and bottom plate 299 of frame 297. The lower ends of these shafts are connected by bolts 307 to the upper ends of the square rods 268 and 269, these shafts forming the upper extensions of these rods and thereby providing pivotal support for the upper ends. Each of the levers is provided with a spring 308 for biasing the lever against the attraction of the levelling magnet for the movable cores. Adjustable stops 310 are provided on the ends of the other arms 311 of the levers. These stops engage an abutment 312 secured between the top and bottom plates of the magnet frame to limit the movement of the levers by their biasing springs.

50 When the car is at rest at a floor, the coil of the levelling magnet is not energized. Under such conditions, springs 303 hold levers 304 and 305 in positions with their stops in engagement with abutment 312. As a consequence, square rods 268 and 269 are held in positions with the operating rollers 281 on arms 278 and 280 in non-retracted positions, that is, at points immediately adjacent end portions 295 of the cam for the floor at which the car is positioned, but slightly disengaged therefrom. As previously pointed out, under such conditions the contacts of levelling switches L1U, L2U, L4U, L1D, L2D and L4D are separated and the contacts of levelling switches L3U and L3D are engaged.

65 The coil of the levelling magnet is energized upon the establishment of circuits incident to the starting of the car. Upon being energized, the levelling magnet acts to pull its cores 300 and 301 inwardly. This causes counterclockwise movement of square rod 268 and clockwise movement of square rod 269 as viewed in Figure 2, moving operating arms 278 and 280 into retracted positions, that is, where the operating rollers 281 carried thereby are clear of the levelling cams. The square rods also act through tubular

members 264 and 265 to move operating cams 271 and 272 for the up and down levelling switches respectively into positions where the contacts of levelling switches L1U, L2U, L4U, L1D, L2D and L4D engage and the contacts of levelling switches L3U and L3D separate.

As movement of the car takes place, the operating arms 278 and 280 are moved by the synchronous crosshead in accordance with movement of the elevator car. Also, the levelling cams are rotated by shaft 285 in accordance with the movement of the car. The rollers 281 on the ends of arms 278 and 280 clear the cams for the floors at which no stops are made as they run by these cams. However, they are released for cooperation with the cam for the floor at which a stop is being made. When the car reaches a certain distance from such floor, the levelling magnet is deenergized. Springs 303 thereupon act to effect opposite movement of square rods 268 and 269, moving operating arm 278 clockwise and operating arm 280 counterclockwise as viewed in Figure 2. Assuming upward travel of the car, for example, deenergization of the levelling magnet occurs at such point that the roller on the end of up operating arm 278 engages the portion of the working face of the levelling cam for the floor at which the stop is being made which is of maximum radius. The roller on the end of the down operating arm 280, however, is not opposite the working face of the cam, so that it does not strike the cam, rotative movement of this arm being stopped by the engagement of adjustable stop 311 on lever 305 with abutment 312. As a result, the contacts of up levelling switches 35 L1U, L2U and L4U are maintained engaged and those of up levelling switch L3U are maintained separated. The contacts of down levelling switches L1D, L2D and L4D, however, separate and those of down levelling switch L3D engage.

As the car arrives at a point still closer to the floor, the levelling cam reaches a position with respect to the roller on up arm 278 which permits the opening of levelling switch L1U. Just before the car arrives at the floor, the cam reaches a point which permits the opening of levelling switches L2U and L4U and the closing of levelling switch L3U. The operation of the levelling switches above described controls the operation of the car to bring it to a stop level with the landing. Should the car overrun the floor, the cam runs onto the roller on the end of down operating arm 280, causing the opening of levelling switch L3D and the closing of levelling switches L4D and L2D. This controls the operation of the car to return it to the landing. Just before it arrives at the landing, the levelling cam runs off the down roller, effecting the re-opening of switches L4D and L2D and the closing of switch L3D. This brings the car to a stop.

The selector machine has been described with special reference to the aforementioned application of Lewis and Bruns, Serial No. 338,872, filed June 5, 1940, which embodies a disclosure of the selector machine as applied to a particular control of an elevator car. Stationary contacts and cooperating brushes for controlling the lighting of the hall lanterns are not shown in such application but the brushes would be provided on the motor advance panel to obtain long light advance.

It is to be understood that the selector machine is not limited in its application to the particular circuits shown in the aforementioned Lewis

and Bruns application or to the particular control disclosed therein. The invention is applicable to various types of control systems and the arrangement of the contacts on the panels and cross bars depends upon the particular control system to which the invention is applied. Also, some of the features of the invention may be utilized in certain control systems and not in others. In certain instances the synchronous crosshead may be omitted and the brushes which otherwise would have been carried thereby, if provided, placed on the distance advance panel. Also, in certain instances, especially where hall lanterns are not provided, the motor advance crosshead may be omitted and any brushes which otherwise would have been carried thereby, placed on the distance advance crosshead. Also, various parts of the selector machine may be arranged as separate units if desired. Details of the construction of the embodiment described may be considerably modified. The distance advance crosshead may be operated at a rate with respect to the floor bars at some other multiple of the speed of the car and the acceleration and retardation portions of a short floor run may be retarded in some ratio other than half and half.

It is not intended to enumerate all the variations which may be made, as many other than those mentioned may be effected without departing from the spirit and scope of the invention. Therefore it is intended that all matter contained in the above description or shown in the accompanying drawings shall be interpreted as illustrative and not in a limiting sense.

What is claimed is:

1. Control mechanism for an elevator car comprising, a plurality of switches for controlling acceleration of the car, and means dependent on car movement during starting of the car from a floor at which it was stopped for successively operating said switches respectively at points increasing predetermined distances from such floor as the car reaches such points to increase the speed of the car.

2. Control mechanism for an elevator car comprising, a movable member, means for moving said movable member during starting of the car at a rate which is a certain proportion to the rate of car movement, a plurality of switches for controlling acceleration of the car, and means actuated by said movable member during said movement thereof for operating said switches in sequence.

3. Control mechanism for an elevator car comprising, a movable member, means for moving said movable member in accordance with car movement and at a rate which is a certain proportion to the rate of car movement, a second movable member, means for moving said second member in accordance with car movement in the same direction as the first movable member and at a rate which is greater than said certain proportion until it has advanced during starting of the car a certain amount with respect to said first movable member, a plurality of switches for controlling acceleration of the car, and means operable by said second movable member during said advance thereof for operating said switches.

4. Control mechanism for an elevator car comprising, a plurality of stationary members, one for each of a plurality of floors, spaced in accordance with the distance between the floors for which they are provided, a movable member, means operable by car movement for moving said movable member with respect to said sta-

tionary members at a rate which is a certain proportion to the rate of car movement to advance said member during starting of the car a certain amount with respect to the car, a plurality of switches for controlling acceleration of the car, and means operable by said movable member during said advance thereof for operating said switches.

5. Control mechanism for an elevator car comprising, a plurality of stationary members, one for each of a plurality of floors, spaced in accordance with the distance between the floors for which they are provided, a movable member, means operable by car movement for moving said movable member with respect to said stationary members at a certain rate and in a direction with respect to said stationary members corresponding to the direction of movement of the car, a second movable member, means operable by car movement for moving said second movable member in the same direction as the first named movable member but at a rate during the starting of the car which is a multiple of said certain rate until it has advanced a certain amount with respect to said first named movable member and for thereafter moving it in unison therewith, a plurality of switches for controlling acceleration of the car, and means operable by said second movable member during said advance thereof for operating said switches in a predetermined sequence.

6. Control mechanism for an elevator car comprising, a plurality of stationary members, one for each of a plurality of floors, spaced in a certain proportion to the distance between the floors for which they are provided, a movable member, means operable incident to the starting of the car for moving said movable member with respect to said stationary members in a direction with respect to said stationary members corresponding to the direction of movement of the car to an advanced position and for thereafter moving said movable member at a rate with respect to said stationary members in accordance with movement of the car in the hatchway, a second movable member, means operable by car movement for moving said second movable member in the same direction as the first named movable member but at a rate with respect to said stationary members which during the starting of the car is a multiple of said first named rate until it has advanced a certain amount and for thereafter moving it in unison with said first named movable member, a plurality of switches for controlling acceleration of the car, and means operable by said second movable member during said advance thereof for operating said switches in a predetermined sequence.

7. Control mechanism for an elevator car comprising, a plurality of switches, means actuated by car movement as the car leaves a floor at which it was stopped for operating said switches in sequence as the car reaches points predetermined distances from such floor, and means operable by car movement for effecting reverse operation of said switches in reverse sequence as the car reaches points predetermined distances from the floor at which a stop is to be made.

8. Control mechanism for an elevator car comprising, switching mechanism for controlling acceleration and retardation of the car, said switching mechanism being in neutral position while the car is stopped at a floor, means actuated by car movement for causing operation of said switching mechanism out of neutral position to control said acceleration during starting of the car from a

5 floor until the car reaches a point a certain distance from such floor, and means actuated by car movement from the time the car reaches a point a certain distance from the floor at which a stop is to be made until it arrives at such floor for causing operation of said switching mechanism back to said neutral position to control retardation of the car.

9. Control mechanism for an elevator car comprising, a movable member, means actuated in accordance with car movement for moving said movable member during starting of the car from a floor at a rate which is a certain proportion to the rate of car movement until the car reaches a point a certain distance from said floor and for thereafter continuing movement of said movable member but at a rate with respect to car movement which is a fraction of said certain proportion, and means for stopping said movable member upon the arrival of the car a certain distance from the floor at which a stop is to be made and for maintaining it so until the car is brought to a stop at such floor.

10. Control mechanism for an elevator car comprising, a plurality of stationary members, one for each of a plurality of floors served by the car, spaced in accordance with the distance between the floors for which they are provided, a stationary contact on each stationary member, a member adapted for movement with respect to said stationary members, a contact carried by said movable member positioned to engage said stationary contacts when the car is stopped at the respective floors for which such contacts are provided, means actuated by car movement for moving said movable member during starting of the car at a multiple of a rate which bears the same relation to the rate of car movement as the distance between stationary members bears to the distance between the floors for which such members are provided until it has advanced a certain amount and thereafter at said rate, and means for stopping said movable member either during said advance or movement subsequent thereto upon the contact carried thereby engaging said stationary contact for a floor at which a stop is to be made and for maintaining it in such position until the car is brought to a stop at such floor.

11. Control mechanism for an elevator car comprising, a movable member, means actuated in accordance with car movement for moving said movable member during starting of the car in a certain ratio with respect to car movement until it has advanced a certain amount and for thereafter continuing movement of said movable member in accordance with car movement but in a ratio with respect to car movement which is a fraction of said certain ratio, means for stopping said movable member upon the arrival of the car at a certain distance from the floor at which a stop is to be made and for maintaining it so until the car is brought to a stop at such floor, thereby bringing said movable member into correspondence with the position of the car, and switching mechanism actuated by said movable member during its said advance with respect to the car for controlling acceleration of the car and by the continued movement of the car after the stopping of said movable member for controlling retardation of the car.

12. Control mechanism for an elevator car comprising, a movable member, means actuated in accordance with car movement for moving said movable member during starting of the car in a

certain ratio with respect to car movement to advance said movable member a certain amount and thereafter continuing movement of said movable member in accordance with car movement but in a ratio with respect to car movement which is half of said certain ratio, and means for stopping said movable member during a full speed run upon the arrival of the car at a certain distance from the floor at which a stop is to be made and during a short floor run during said advance of said movable member upon the car reaching a point half the distance of the run and for maintaining said movable member in such position while the car is brought to a stop at such floor, thereby bringing said movable member into correspondence with the position of the car.

13. Control mechanism for an elevator car comprising, switching mechanism for controlling acceleration and retardation of the car, said switching mechanism being in neutral position while the car is stopped at a floor, a plurality of stationary members, one for each of a plurality of floors served by the car, spaced in accordance with the distance between the floors for which they are provided, a member adapted for movement with respect to said stationary members and having a certain relationship thereto when the car is stopped at the respective floors, means actuated by car movement for moving said movable member during starting of the car at a multiple of a rate which bears the same relation to the rate of car movement as the distance between stationary members bears to the distance between floors for which such members are provided until it has advanced a certain amount and thereafter at said rate, means for stopping said movable member either during said advance or movement subsequent thereto upon its reaching said certain relationship with respect to said stationary member for a floor at which a stop is to be made and for maintaining it in such position until the car is brought to a stop at such floor, means actuated by said movable member during said advance thereof for causing operation of said switching mechanism out of neutral position to control said acceleration of the car, and means actuated by car movement from the time said movable member is brought to a stop until the car arrives at the floor at which it is to be stopped for causing operation of said switching mechanism back to said neutral position to control retardation of the car.

14. Control mechanism for an elevator car comprising, a plurality of stationary members, one for each of a plurality of floors served by the car, spaced in accordance with the distance between the floors for which they are provided, a movable member having a definite position with respect to said stationary members when the car is stopped at the respective floors for which such stationary members are provided, means actuated in accordance with car movement for moving said movable member during starting of the car at a multiple of a rate which bears the same relation to the rate of car movement as the distance between stationary members bears to the distance between floors for which such members are provided until it has advanced a certain amount and for thereafter moving said movable member at said rate, means for stopping said movable member upon its arrival at said definite position with respect to said stationary member for a floor at which a stop is to be made, the continued movement of the car until it is brought

5 to a stop at such floor taking up the advance of said movable member, and switching mechanism actuated by said movable member during its said advance for controlling acceleration of the car and by said car during said continued movement thereof after the stopping of said movable member for controlling retardation of the car.

15. Control mechanism for an elevator car comprising, a plurality of stationary members, one 10 for each of a plurality of floors, spaced in accordance with the distance between the floors for which they are provided, a member movable with respect to said stationary members, means for initially moving said movable member to an advanced position with respect to the car and for thereafter maintaining it in such position, means adapted upon arrival of said movable member 15 in a certain position with respect to the stationary member for a floor at which a stop is to be made to bring said movable member to a stop, a plurality of switches, means actuated at a rate in a certain proportion to the rate of car movement during starting of the car for operating said switches in sequence as the car reaches 20 points predetermined distances from the floor from which it is started, and means rendered effective upon the stopping of the first movable member and operable by movement of the car for effecting reverse operation of said switches in 25 reverse sequence as the car reaches points predetermined distances from the floor at which a stop is to be made.

16. Control mechanism for an elevator car comprising, a plurality of stationary members, 30 one for each of a plurality of floors, spaced in accordance with the distance between the floors for which they are provided, a member movable with respect to said stationary members, means for initially moving said movable member to an advanced position with respect to the car and for thereafter maintaining it in such position, circuit 35 controlling means operable by relative movement of said movable member with respect to said stationary members upon arrival of said movable member at a certain position with respect to the stationary member and adapted upon arrival in such position with respect to the stationary member for a floor at which a stop is to be made, either during said advance or during said movement in advanced position, to bring said movable member to a stop, a second movable member, means for moving said second movable member in accordance with car movement initially at a rate in a certain ratio with respect to the rate of 40 car movement until it has advanced a certain amount with respect to the car and thereafter at half said initial rate, means operable after the stopping of the first movable member to bring said second movable member to a stop, a plurality 45 of switches, means operable by said second movable member during said initial movement thereof for operating said switches in a certain sequence, and means operable by said car after said second movable member has been brought to a stop for effecting reverse operation of said switches in reverse sequence.

17. Control mechanism for an elevator car comprising, a plurality of stationary members, one for each of a plurality of floors, spaced in a certain proportion to the distance between the floors for which they are provided, a stationary contact on each of said stationary members, a member movable with respect to said stationary members, a contact carried by said movable member for engaging said stationary contacts, a

motor for initially moving said movable member to an advanced position with respect to the car and for thereafter maintaining it in such position, the engagement of said contact carried thereby with a stationary contact for a floor at which a stop is to be made, either during said advance or during said movement in advanced position being adapted to deenergize said motor to bring said movable member to a stop, a second movable member, means for moving said second movable member in accordance with car movement initially at a rate in a certain ratio with respect to the rate of car movement until it has advanced a certain amount with respect to the car and thereafter at a rate corresponding to the rate of car movement, means operable after the stopping of the first movable member to bring said second movable member to a stop, a plurality of switches, means operable by said second movable member during said initial movement thereof for operating said switches to control acceleration of the car, and means operable by said car during its continued movement after said second movable member has been brought to a stop for operating said switches to control retardation of the car.

18. Control mechanism for an elevator car comprising, a plurality of stationary members, one for each of a plurality of floors, spaced in a certain proportion to the distance between the floors for which they are provided, a stationary contact on each of said stationary members, a member movable with respect to said stationary members, a contact carried by said movable member positioned to engage said stationary contacts when the car is stopped at the respective floors for which such contacts are provided, means for moving said movable member with respect to said stationary members in accordance with the direction of car movement to place said contact carried thereby a certain distance in advance of the position corresponding to the position of the car and for thereafter maintaining said movable member in said advanced position, the engagement of said contact carried thereby with a stationary contact for a floor at which a stop is to be made, either during said advance or during its movement in advanced position being adapted to bring said member to a stop, a second member movable with respect to said stationary members and having a certain position with respect thereto when the car is stopped at the respective floors, means operable by car movement for moving said second movable member with respect to said stationary members in accordance with the direction of car movement but at a multiple of a rate which bears the same relation to the rate of car movement as the distance between stationary members bears to the distance between floors for which such members are provided until it has advanced a certain amount and for thereafter moving it at said rate, means operable by said second movable member as it arrives in said certain position with respect to the stationary member for said floor at which a stop is to be made adapted to bring said second movable member to a stop, a plurality of switches, means operable by said second movable member during said advance thereof for operating said switches in a predetermined sequence to control acceleration of the car, and means operable by said car during its continued movement after said second movable member has been brought to a stop for operating said switches in reverse sequence to control retardation of the car.

19. Control mechanism for an elevator car serving a plurality of floors comprising, flexible means, means actuated by car movement for driving said flexible means, a member movable in the same direction as said flexible means, additional flexible means, rotatable means pivotally mounted on said movable member and engaging said first named flexible means and said additional flexible means, means for yieldably preventing rotative movement of said rotatable means to effect movement of said movable member, said additional flexible means and first named flexible means as a unit during initial movement of the car, means for stopping movement of said additional flexible means upon the car reaching a point a certain distance from the floor from which it was started, said yielding means thereupon yielding to permit rotative movement of said rotatable means, a plurality of stationary stopping members, one for each of said floors, means carried by said movable member for engaging said stopping member for the floor at which a stop is to be made, either during movement of said movable member and flexible means as a unit or after said additional flexible means has been brought to a stop to bring said movable member to a stop, continued movement of said first named flexible means by the car after said movable member is brought to a stop acting to rotate said rotatable means to effect reverse movement of said additional flexible means, switching mechanism, and means operated by said movement of said additional flexible means for operating said switching mechanism.

20. Control mechanism for an elevator car serving a plurality of floors comprising, a sprocket chain, means actuated by car movement for driving said sprocket chain in a direction corresponding to the direction of car movement, a crosshead, a sprocket wheel pivotally mounted on said crosshead meshing on one side thereof with said chain, an additional sprocket chain extending parallel with the first named chain and meshing with said sprocket wheel on the other side thereof, means for yieldably preventing rotative movement of said wheel thereby effecting movement of said crosshead and additional chain along with said first named chain as a unit during initial movement of the car, means for stopping movement of said additional chain upon the car reaching a point a certain distance from the floor from which it was started, said yielding means thereupon yielding to permit rotative movement of said wheel, a plurality of stationary stopping members, one for each of said floors, means carried by said crosshead for engaging said stopping members to bring said crosshead to a stop upon the arrival of the car at a predetermined distance from the respective floors for which said members are provided, continued movement of said first named chain by the car after said crosshead is brought to a stop acting to rotate said wheel to effect reverse movement of said additional chain, switching mechanism, and means operated by said additional chain during said initial movement of the car for operating said switching mechanism and when said crosshead is brought to a stop for restoring said switching mechanism to unoperated condition.

21. Control mechanism for an elevator car comprising, a plurality of switches, rotatable means having a neutral position, means operable by said rotatable means upon rotative movement thereof from neutral in either direction

for closing said switches in sequence and upon return thereof to neutral for opening said switches in reverse sequence, flexible driving means for said rotatable means, additional flexible means, means actuated by car movement for driving said additional flexible means in a direction corresponding to the direction of car movement, a movable member, a wheel pivotally mounted on said movable member engaging each of said flexible means, means for yieldably preventing rotative movement of said wheel to effect movement of said first named flexible means in the same direction as and in synchronism with said additional flexible means during initial movement of the car to effect operation of said rotatable means in one or the other direction from neutral to effect the closing of said switches in sequence as the car reaches points predetermined distances from the floor from which it is started, means for stopping movement of said first named flexible means after closing the last of said switches, said yielding means thereupon yielding to permit rotative movement of said wheel, an elongated member extending parallel to the path of movement of said movable member, a plurality of lugs, one for each of a plurality of floors served by the car secured to said elongated member in spaced relation in accordance with the distance between the floors for which they are provided, a pair of oppositely disposed pawls, one for each direction of car movement, carried by said movable member for engaging said lugs, and means for operating said elongated member to extend said lugs into and out of the path of movement of said pawls, said pawl for the direction for which said movable member is being actuated acting upon extension of said lugs to engage the next lug in said direction therefrom to bring said movable member to a stop, continued movement of said additional flexible means by the car after said movable member is brought to a stop acting to rotate said wheel to effect reverse movement of said first named flexible means to return said rotatable means to neutral to effect the closing of said switches in reverse sequence as the car reaches points predetermined distances from the floor at which a stop is to be made.

22. Control mechanism for an elevator car comprising, a plurality of switches, a plurality of rotatable operating cams for said switches, one for each switch, for effecting operation of their respective switches in sequence, a uniform motion cam, means operable by said uniform motion cam upon rotative movement thereof from neutral in either direction to effect rotative movement of said operating cams to operate said switches and upon return thereof to neutral to effect reverse rotative movement of said operating cams to restore said switches to their former condition, a driving wheel for said uniform motion cam, flexible driving means for said wheel arranged in a loop, additional flexible means arranged in a loop, means actuated by car movement for driving said additional flexible means in a direction corresponding to the direction of car movement, a movable member, a wheel pivotally mounted on said movable member engaging one run of each of said flexible means, means for yieldably preventing rotative movement of said second wheel to effect movement of said first named flexible means in the same direction as and in synchronism with said additional flexible means during initial movement of the car to effect operation of said uni-

form motion cam in one or the other direction from neutral to cause operation of said switches in sequence as the car reaches points predetermined distances from the floor from which it is started, means for stopping movement of said first named flexible means after operation of said switches, said yielding means thereupon yielding to permit rotative movement of said second named wheel by said additional flexible means during continued movement of the car, a pair of pawls carried by said movable member, one for up car travel and one for down car travel, an elongated member extending parallel to the path of movement of said movable member, a plurality of lugs, one for each of a plurality of floors served by the car secured to said elongated member in spaced relation in accordance with the distance between the floors for which they are provided and adapted to be engaged by said pawls, said elongated member being biased to extend said lugs into the path of movement of said pawls, and electromagnetically operable means for operating said elongated member to retract said lugs into position to clear said pawls during movement of said movable member, said pawl for the direction for which said movable member is being actuated acting upon extension of said lugs to engage the next lug in said direction therefrom to bring said movable member to a stop, continued movement of said additional flexible means by the car after said movable member is brought to a stop acting to rotate said second named wheel to effect reverse movement of said first named flexible means to return said uniform motion cam to neutral to cause reverse operation of said switches in reverse sequence as the car reaches points predetermined distances from the floor at which a stop is to be made.

23. Control mechanism for an elevator car comprising, a plurality of switches, an operating cam for each of said switches, a pinion connected with said cams to effect rotative movement thereof, said cams being set to effect operation of their respective switches in sequence upon their rotative movement in one direction and reverse operation of said switches in reverse sequence upon rotative movement thereof in the opposite direction, a slidable rack for rotating said pinion, a heart-shaped cam adapted upon rotative movement from neutral position in either direction to effect movement of said rack to rotate said pinion to effect rotative movement of said cams in said one direction and upon return thereof to neutral position to effect reverse movement of said rack to effect rotative movement of said cams by said pinion in said opposite direction, and means actuated by car movement for effecting rotative movement of said heart-shaped cam in one direction or the other out of neutral, depending upon the direction of car movement, as the car leaves the floor from which it is started and for causing opposite rotative movement of said heart-shaped cam to return it to neutral as the car arrives at a floor at which a stop is being made.

24. Control mechanism for an elevator car comprising, a movable member, means actuated in accordance with car movement for moving said movable member during starting of the car in a certain ratio with respect to car movement to advance said movable member with respect to the car and on a full speed run until it has advanced a certain amount with respect to the car and thereafter continuing movement of said movable member in accordance with car movement but in

a ratio with respect to car movement which is half of said certain ratio, means for stopping said movable member during a full speed run upon the arrival of the car at a certain distance from the floor at which a stop is to be made and during a short floor run upon the car reaching a point half the distance of the run and for maintaining it so until the car is brought to a stop at such floor, thereby bringing said movable member into correspondence with the position of the car, switching mechanism actuated by said movable member during its said advance with respect to the car for controlling acceleration of the car and by the continued movement of the car after the stopping of said movable member for controlling retardation of the car, stationary circuit controlling means for each of the floors served by the car, and contacting means carried by said movable member for engaging said circuit controlling means before the car reaches said point half the distance of a short floor run for arresting acceleration.

25. Control mechanism for an elevator car serving a plurality of floors comprising, flexible means, means actuated by car movement for driving said flexible means, a member movable in the same direction as said flexible means, rotatable means pivotally mounted on said movable member and engaging said flexible means, additional flexible means engaging said rotatable means, means for yieldably preventing rotative movement of said rotatable means to effect movement of said movable member, additional flexible means and first named flexible means as a unit during initial movement of the car, means for stopping movement of said additional flexible means upon the car reaching a point a certain distance from the floor from which it was started, said yielding means thereupon yielding to permit rotative movement of said rotatable means, switching mechanism, and means operated by said additional flexible means during said movement thereof for operating said switching mechanism.

26. Control mechanism for an elevator car serving a plurality of floors comprising, a sprocket chain, means actuated by car movement for driving said sprocket chain in a direction corresponding to the direction of car movement, a crosshead, a sprocket wheel pivotally mounted on said crosshead and meshing on one side thereof with said chain, an additional sprocket chain extending parallel with the first named chain and meshing with said sprocket wheel on the other side thereof, means for yieldably preventing rotative movement of said wheel and thereby effecting movement of said crosshead and additional sprocket chain along with said first named sprocket chain as a unit during initial movement of the car, switching mechanism, means operated by said additional chain during said movement thereof for operating said switching mechanism, and means for stopping movement of said additional chain upon the car reaching a point a certain distance from the floor from which it was started, said yielding means thereupon yielding to permit rotative movement of said sprocket wheel.

27. Control mechanism for an elevator car comprising, a plurality of switches, a plurality of rotatable operating cams for said switches, one for each switch, for effecting operation of their respective switches in sequence, a uniform motion cam, means operable by said uniform motion cam upon rotative movement thereof from neutral in either direction to effect rotative movement of

said operating cams to operate said switches, a driving wheel for said uniform motion cam, flexible driving means for said wheel arranged in a loop, additional flexible means arranged in a loop, means actuated in accordance with car movement for driving said additional flexible means in a direction corresponding to the direction of car movement, a movable member, a wheel pivotally mounted on said movable member engaging one run of each of said flexible means, means for yieldably preventing rotative movement of said second wheel to effect movement of said first named flexible means in the same direction as and in synchronism with said additional flexible means during initial movement of the car to effect operation of said uniform motion cam in one or the other direction from neutral to cause operation of said switches in sequence as the car reaches points predetermined distances from the floor from which it is started, and means for stopping movement of said first named flexible means after operation of said switches, said yielding means thereupon yielding to permit rotative movement of said second named wheel by said additional flexible means during continued movement of the car.

28. Control mechanism for an elevator car serving a plurality of floors comprising, flexible means, means actuated by car movement for driving said flexible means, a member movable in the same direction as said flexible means, additional flexible means, rotatable means pivotally mounted on said movable member and engaging said first named flexible means and said additional flexible means, yieldable means acting on said rotatable means to cause movement of said movable member, additional flexible means and first named flexible means as a unit during initial movement of the car, a plurality of stationary stopping members, one for each of said floors, means carried by said movable member for engaging said stopping member for the floor at which a stop is to be made to bring said movable member to a stop, continued movement of said first named flexible means by the car after said movable member is brought to a stop acting to rotate said rotatable means to effect reverse movement of said additional flexible means, said yieldable means yielding to permit such movement, switching mechanism, and means operated by said reverse movement of said additional flexible means for operating said switching mechanism.

29. Control mechanism for an elevator car serving a plurality of floors comprising, a sprocket chain, means actuated in accordance with car movement for driving said sprocket chain in a direction corresponding to the direction of car movement, a crosshead, a sprocket wheel pivotally mounted on said crosshead meshing on one side thereof with said chain, an additional sprocket chain extending parallel with the first named chain and meshing with said sprocket wheel on the other side thereof, yieldable means acting on said sprocket wheel for preventing rotative movement thereof to cause movement of said sprocket wheel, additional sprocket chain and first named sprocket chain as a unit during initial movement of the car, an elongated member extending parallel to the path of movement of said crosshead, a plurality of lugs, one for each of said floors, secured to said elongated member in spaced relation in accordance with the distance between the floors for which they are provided, a pair of oppositely disposed pawls, one

for each direction of car movement, carried by said crosshead for engaging said lugs for the floors at which stops are to be made to bring said crosshead to a stop, continued movement of said first named chain by the car after said crosshead is brought to a stop acting to rotate said sprocket wheel to effect reverse movement of said additional sprocket chain, said yieldable means yielding to permit such movement, switching mechanism, and means operated by said reverse movement of said additional sprocket chain for operating said switching mechanism.

30. Control mechanism for an elevator car serving a plurality of floors comprising, a sprocket chain, means actuated by car movement for driving said sprocket chain in a direction corresponding to the direction of car movement, a crosshead, a sprocket wheel pivotally mounted on said crosshead meshing on one side thereof with said chain, an additional sprocket chain extending parallel with the first named chain and meshing with said sprocket wheel on the other side thereof, means for yieldably preventing rotative movement of said wheel to effect movement of said crosshead and additional chain along with said first named chain as a unit during initial movement of the car, a second crosshead, a sprocket wheel carried by said second crosshead for meshing with the first named sprocket chain

5 to drive said second crosshead at half the speed of said chain, means for stopping movement of said additional chain upon the car reaching a point a certain distance from the floor from which it was started, said yielding means thereupon yielding to permit rotative movement of said first named wheel, said crossheads thereafter moving as a unit at half the speed of said first named chain, a plurality of stationary stopping members, one for each of said floors, means carried by said first named crosshead for engaging said stopping members to bring said first named crosshead to a stop upon the arrival of the car at a predetermined distance from the respective floors for which said members are provided, continued movement of said first named chain by the car after said first named crosshead is brought to a stop acting to rotate said first named wheel to effect reverse movement of said additional chain and to continue movement of said second crosshead at half the speed of said first named chain, switching mechanism, and means operated by said additional chain during said initial movement of the car for operating said switching mechanism and when said first named crosshead is brought to a stop for restoring said switching mechanism to unoperated condition.

EDWARD LEE DUNN.
